HEAT EXCHANGE SYSTEM

Franz Dauskardt, Hamburg-Bergedorf, Germany, assignor to Aktiebolaget Separator, Stockholm, Sweden, a corporation of Sweden

Application April 14, 1953, Serial No. 348,704

Claims priority, application Germany April 18, 1952

3 Claims. (Cl. 257—215)

This invention relates to systems for heating liquids and more particularly to those comprising heat exchangers for heating liquids in the beverage industry, e.g. beer and milk, and for similar purposes. The invention will be described in connection with the pasteurization of milk, but only for illustrative purposes, it being understood that the invention is not limited to this use.

The pasteurization of milk is carried out in systems comprising several apparatus, of which a heat exchanger wherein the milk is pasteurized, a water heater, and a pump for pumping the hot water through the heat exchanger, are the most important. Instead of water, steam may be used as the heating medium, but the use of steam has the drawback that parts of the milk may be heated to such a high temperature that deleterious changes of some substances in these parts take place. Water is therefore preferred, and systems in which hot water is used are generally provided with a device for producing hot water. This device and the other parts of the system have heretofore been erected separately, the device for producing hot water often being located in the cellar or boiler room in the building in which the system is installed. This has several drawbacks. The piping is extensive and complicated, considerable space is required, and the erection of the different parts is expensive.

According to the present invention the aforementioned three parts, namely, the plate heat exchanger, the hot water heater and the circulation pump, are built together in a closed unit. In order to make it clearly understood and readily carried into effect, the invention will be described with reference to the accompanying drawings, in which

Fig. 1 is a schematic view of one form of the new system;

Figs. 2 and 3 are similar views of modified forms of the system, and

Fig. 4 is an enlarged sectional view of the three-way valve cock illustrated in Fig. 3.

According to Fig. 1, the water is heated by means of a steam ejector 1 and the pasteurization of the milk takes place in the plate heat exchanger 2. The latter is connected to a water accumulator 3 so as to form a hot water circuit in which the heating water, after having passed through the heat exchanger 2, is returned to the accumulator 3. The accumulator 3, which may have a small volume compared to the heat exchanger, is provided with an overflow pipe 4 through which condensate formed by the steam led into the ejector is discharged. This overflow pipe is directly attached to the frame formed by the water accumulator 3. A pump 5 for the circulation of the heating water is placed at the bottom of the accumulator and sucks the hot water directly from it. At its lower end, the accumulator has walls 6a forming a separate compartment 6 to accommodate the shaft 7 of a motor 10, which drives the pump 5. The motor is flanged to the frame formed by the hot

2

water accumulator 3. Water leaking from the packing box 8 flows from the bottom of compartment 6 through pipe 9 down upon the floor, upon which the unit is erected.

In order to compensate for the fluctuations occurring in the heating of the water in the accumulator, a space 11 is provided between its overflow opening and its uppermost wall.

The heating water and the milk to be heated are passed counter-currently through the heat exchanger 2, the main flow direction of the milk being indicated by the broken line and that of the heating water being indicated by the full line. The cooled heating water from the heat exchanger 2 as well as steam are simultaneously fed into the steam ejector 1 where the water is heated to the required temperature. The heated water then passes through the accumulator 3, as shown generally by the broken line, to the suction opening of the pump 5. It then flows through the heat exchanger 2 back to the steam ejector, thus commencing a new cycle.

According to Fig. 2 the heating of the water is carried out in heat exchanger 1a of the plate type. In the exchanger 1a, the heat from the steam is transferred through the plates from one side to the other, where it is taken up by the water flowing over the latter side. As in Fig. 1, the water accumulator is indicated at 3 and the milk heater at 2. The main flow direction of the milk through heater 2 is also in this case represented by the broken line, while that of the water is represented by the full line. The use of a set of plates for heating the water not only allows a closed unit but also has the advantage that the plates can be used in various numbers in the heat exchanger 1a, which can thus be adjusted to varying working conditions. By increasing the number of plates in heater 1a, the heating effect will be higher, and vice versa. Plate heat exchangers also have the characteristic feature that the plates can easily be removed from the frame of the exchanger for cleaning. This is particularly advantageous for the heat exchanger in which the water is heated, since boiler-scale may deposit on the plates, and if waste steam is used for heating, oil from this steam may gradually cover the heat transfer surfaces. Preferably, the plates in the exchanger 1a are similar to those in the exchanger 2, so that the number of different plates will be minimized.

As illustrated in Fig. 2, the water discharged from plate heat exchanger 2 passes by way of line 30 into the accumulator 3, then through this accumulator, as shown generally by the broken line, to the inlet of pump 5, and then through line 31 to the plate heat exchanger 1a where it is heated by the steam entering from line 32, the steam condensate passing to the discharge line 33. From plate heat exchanger 1a, the hot water passes through connection 34 to the heat exchanger 2 where it heats the milk entering and discharging at 35 and 36, respectively, the water then passing to the line 30 to repeat the cycle. Thus, the connecting lines 30 and 31 and the connection 34 comprise means interconnecting the accumulator 3, pump 5, heat exchanger 1a and plate heater 2 to form a closed circulation path for the water.

In a unit made according to Fig. 1, a quantity of water corresponding to the amount of steam fed into and condensed in the accumulator 3 will flow away through the pipe 4. Since the temperature of this water is high, generally about 200° F., this means a considerable loss of heat. This loss can be avoided by the arrangement shown in Fig. 3, wherein a float is disposed in the accumulator and has its lever connected with a three-way valve cock, to which the water returning from the heater 2 is led. Under the influence of the movements

of this float, the water is divided into two regulated streams. At normal conditions the main part of the water is led to the steam ejector 1 and the rest of it is discharged from the water circulation system, for example, to a container for feed water to the boiler from which steam is supplied to the ejector 1.

According to Fig. 3, the lever 19 of float 12 is connected to the rotatable plug of a three-way valve cock 13, to which water from plate heat exchanger 2 is led through return piping 14 and from which the main part of this water is normally led through pipe 16 to the ejector 1. The remaining water fed to cock 13 is led away from the water circulation system through a pipe 17 to a container (not shown) for feed water. In order to maintain the atmospheric pressure in the space 11 above the water surface, an opening 15 is arranged in the top wall of the accumulator 3 or in other suitable position in relation to this surface.

The cock 13 is shown in section on an enlarged scale in Fig. 4. The plug 18 of the cock is rigidly connected with the float lever 19 which is freely movable within a recess 20 in the cock housing. This housing also has an inlet opening 22 to which the pipe 14 is connected, an outlet opening 23 to which the pipe 16 is connected, and an outlet opening 24 to which the pipe 17 is connected. When the water level in the accumulator 3 sinks, the float lever 19 swings downwardly and thus turns the plug 18 clockwise as shown in Fig. 4, thereby making the connection between the openings 22 and 23 larger while making the connection between the openings 22 and 24 smaller. The amount of water flowing away through opening 24 and pipe 17 will then be reduced, and the water level in the accumulator 3 will therefore rise as steam fed through the ejector 1 is condensed in the water. With a rising water level, the regulating operation will be the opposite; that is, the flow through the opening 24 will increase until equilibrium is reached. In this way the quantity of circulating heating water is kept practically constant while, at the same time, the loss of heat in the water flowing away is prevented.

It will be apparent that in all of the illustrated embodiments of the invention, the water heater 1 (1^a), plate heater exchanger 2 and pump 5 are connected in series with and supported as a unit on the accumulator 3 which, in turn, is supported on the frame 26 resting upon the floor. Thus, all of these parts are in effect supported in a unitary assembly by the frame 26. This frame, if desired, could be arranged to directly support one of the other parts, such as the heat exchanger 2, instead of the accumulator. It will also be apparent that the float-controlled valve 13 of Fig. 3 and the over-

flow pipe 4 of Fig. 1 each constitute a means for maintaining a substantially constant water level in the accumulator 3, by diverting from the circuit a quantity of water corresponding to that formed in the circuit by condensed steam from the ejector 1.

It will also be apparent that the part 3 not only serves as an accumulator in the circuit for the hot water used in the plate heat exchanger, but also constitutes a hollow press plate for supporting one end of the plate pack of the plate heat exchanger (the exchanger 2 in Figs. 1 and 3, or the exchanger 1^a—2 in Fig. 2). By virtue of this arrangement, it is possible to reduce to a minimum the number of communications between the set of heat exchange plates and the auxiliary apparatus of the system, particularly when the part 3 also serves as a support for the motor-driven pump 5 of the hot water circuit, as illustrated.

I claim:

1. In a plate type heating unit for sterilizing a liquid with the use of hot water as a heating medium and comprising a heat exchanger for heating the water, a water accumulator, a plate heater for heat transmission between the hot water and the liquid to be sterilized, a circulation pump for the hot water and a driving motor connected to the pump, the improvement wherein both the heat exchanger and the plate heater include respective plate packs which together constitute a common plate heat exchange unit, the water accumulator forming an end wall and a support for one end of said common plate heat exchange unit, the pump and motor being mounted on and supported by the lower portion of said accumulator, and means interconnecting the accumulator, the pump, the heat exchanger and the plate heater to form a closed circulation path for the water.
2. The improvement according to claim 1, in which the accumulator has an overflow outlet leading from the interior of the accumulator to the outside thereof.
3. The improvement according to claim 1, in which the accumulator has walls forming a water-free space in its lower portion, the motor having a drive shaft extending through said space to the pump.
